US00D490840S

(12) **United States Design Patent** (10) Patent No.: **US D490,840 S**
Arakaki et al. (45) Date of Patent: ** Jun. 1, 2004

(54) **PROXIMITY INTERFACE FOR
TRANSACTION ACCEPTANCE SYSTEMS**

(75) Inventors: **James S. Arakaki**, Campbell, CA (US);
Mohammad A. Khan, San Jose, CA (US); **David Kevin Pariseau**, Los Altos, CA (US); **Jorge M. Fernandes**, Los Altos Hills, CA (US); **Marcelo Alves Bezerra De Lima**, San Jose, CA (US); **Ahmer Ali Khan**, Mountain View, CA (US); **Kerry D. Brown**, Los Altos Hills, CA (US)

(73) Assignee: **VIVOtech, Inc.**, Santa Clara, CA (US)

(**) Term: **14 Years**

(21) Appl. No.: **29/170,080**

(22) Filed: **Oct. 30, 2002**

(51) LOC (7) Cl. **18-01**

(52) U.S. Cl. **D18/4.4; D18/12**

(57) **CLAIM**

The ornamental design for a proximity interface for transaction acceptance systems, as shown and described.

DESCRIPTION

FIG. 1 is a front perspective view of a proximity interface for transaction acceptance systems showing my new design;

FIG. 2 is a rear perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a right side elevational view thereof; and,

FIG. 8 is a left side elevational view thereof.

The broken line showing the environment in FIG. 1 is for illustrative purposes only and forms no part of the claimed design.
